MANHOLE CONSTRUCTION

Norman C. Mayer, Norwood, Ohio

Application July 26, 1930, Serial No. 470,916

1 Claim. (Cl. 94—35)

My invention relates to an adapter for use in road resurfacing work.

In the past, to the best of my knowledge and belief, when contractors have resurfaced roadways in which manhole casings, valve chambers, and electric ducts are inserted, in order to raise the level of the manhole cap to correspond with the resurfaced level of the road it has been customary to dig up the entire manhole casing and 10 extend the masonry to a desired level, and then re-position the manhole casing so that the top cap receiving portion of the casing will be elevated level with the resurfaced road.

It is the object of my invention to provide an 15 adapter for use in road resurfacing work which will enable the road builder to avoid the necessity of digging up manhole casings and elevating them to a desired level.

Specifically it is the object of my invention to 20 provide an adapter having an annular flanged portion which will be of corresponding size to the dimensions of the manhole cap, and which will have an opening of suitable size to receive the cap and to firmly anchor the adapter on the manhole casing so that the jars brought about by traffic will not tend to loosen the adapter.

The above objects and other objects to which 25 reference will be made in the accompanying description, I accomplish by that certain construction of which I have illustrated a preferred embodiment.

Referring to the drawing:—

Figure 1 is a view partly in section, of a manhole casing prior to the resurfacing of the road, 30 the casing being of usual construction.

Figure 2 is a sectional view showing one way of 35 practicing my invention by the insertion of a manhole adapter within the manhole casing, so that the level at which the manhole cap will be supported will conform to the resurfaced plane of the roadway.

Figure 3 is a sectional view of a manhole adapter.

I have illustrated my invention as applied to 40 a round manhole casing, but it will be understood that my new construction may be employed with different shaped casings, such as are employed for valve chambers, electric ducts, and the like.

50 In Figure 1 I have illustrated the sewer masonry to which the manhole extends at 1. The manhole casing 2 has an annular flanged base 3 which is positioned on the top surface of the masonry wall. The great weight of the manhole

casing, and the fact that the road bed 4 and the roadway surface 5 are filled in about it, will keep the casing in position.

An annular opening 6 in the top of the casing receives the manhole cap indicated at 7. 60

In Figure 2 I have illustrated the manner of use of my novel adapter which (referring to Figure 3) it will be noted, has a flanged portion 8 of similar size as the manhole cap and an annular recessed portion 9 into which the cap 7 will 65 fit.

Depending on the new level of the roadway after it is resurfaced, I provide adapters of different depths so that the roadway may be raised a desired amount. 70

In Figure 2 a depth of resurfacing material is indicated at 10, and the adapter is positioned within the manhole casing so that the cap 7 will be elevated to the new resurfaced level of the road.

The adapter illustrated has bosses 11 having 75 holes 12 therein through which hook bolts 13 having hooked ends 14 which lock against the end surface of the base 3 of the manhole casing, are mounted. Nuts 15 are threaded on the ends of the hook bolts, as indicated, so that the adapter can be firmly held in position in the manhole casing. 80

Supposing that a roadway is resurfaced every ten years. If the level is raised two inches the first ten years and two inches more the second 85 ten years, the first year an adapter two inches long will be required, and after this has been in use for ten years it may be removed and a four inch adapted positioned in the manhole casing.

Having thus described my invention, what I 90 claim as new and desire to secure by Letters Patent, is:—

A manhole adapter for use with a manhole casing having a top lid space and downwardly facing engaging means accessible from its interior, comprising a ring shaped on its lower side to fit said lid space and shaped on its upper side to be fitted by the manhole lid, and having interior upwardly facing engaging means spaced down from its lid receiving part, tie rods, and 95 nuts screwed on the tie rods and engaging over said engaging means of the adapter, said tie rods extending down to enter the interior of the casing and having lower hook portions to engage under the engaging means of the casing, to hold the adapter rigidly unitary with the casing upon tightening of the nuts onto the engaging means of the adapter. 105

NORMAN C. MAYER.
